Attorneys.

UNITED STATES PATENT OFFICE.

HAROLD R. SCHUTZ, OF TOLEDO, OHIO, ASSIGNOR TO THE EDWARD FORD PLATE GLASS CO., OF ROSSFORD, OHIO, A CORPORATION OF OHIO.

ROLL FOR ROLLING MOLTEN GLASS.

Application filed March 3, 1927. Serial No. 172,266.

This invention relates to the manufacture of plate or sheet glass, by the intermittent, as distinguished from the continuous, rolling method.

5 In the use of this method, a quantity of molten glass is customarily deposited in a receptacle in contact at one side with a pair of rolls by which the glass is rolled out in sheet or plate form, the size of the sheet depending on the quantity of glass in the receptacle, all of which is usually rolled out in a single operation. The sheet is then annealed, ground and polished.

The rolls employed are usually of hollow form with a relatively thick solid wall of uniform thickness. These rolls are ordinarily cooled by a circulating air, water or other cooling fluid therethrough, and due to their circular interior form, present a minimum of surface to the cooling medium. The wall must be made of considerable thickness to provide a sufficient mechanical strength, so that a roll of the length ordinarily used will have the necessary resistance to lateral deflection occasioned by the rolling pressure.

It is found in practice that when rolls of this character are at rest the prolonged contact of the molten glass with the portion of the rolls exposed to the receptacle causes a high heating and more rapid expansion of such portions than others of the rolls, resulting in a hump or bulge at such points. When the rolls in this condition are rotated about their axes in the process of reducing the molten glass to sheet form, alternate thin and thick sections are produced in the sheet by the irregular forms of the roll peripheries. The irregular sheet surface must be reduced by grinding, thereby requiring considerably more work and time in the grinding operation than would otherwise be necessary and adding accordingly to the expense of production. It is apparent that the irregular heating of the rolls and the consequent irregular formation of the sheets is also present, but to a less extent, when the rolls are continuously rotated.

In order to reduce to a minimum these irregularities in the thickness of the formed sheet, it has been customary to rotate the rolls faster than would otherwise ordinarily

be the case. This practice, however, produces a sheet having a rounded end of greater length than desired, which it is necessary to cut away to produce a straight end. This results in a considerable loss of glass which could otherwise be used to produce a sheet of greater size.

The object of this invention is to provide a roll which will reduce the above objections to a minimum, and this is accomplished by providing a hollow roll having a relatively thin wall or shell to effect a rapid dissipation of heat therethrough to the interior cooling means and also to provide the interior of said wall with a plurality of ribs or fins both to increase the heat radiating efficiency of the inner surface of the roll and to strengthen or reinforce the thin wall against compressing or deflecting forces.

The invention is fully described in the following specification and one embodiment thereof illustrated in the accompanying drawings, in which,—

Figure 1 is a central longitudinal sectional view, more or less in diagram, of an apparatus embodying the invention for producing rolled sheet or plate glass. Fig. 2 is an enlarged central longitudinal section of one of the rolls embodying the invention, and Fig. 3 is an enlarged cross-section on the line 3—3 in Fig. 2.

Referring to the drawings, 1 designates a receptacle for molten glass 2, such receptacle having an open side, which is closed or partially closed by a pair of rolls 3, 3 between which the glass from the receptacle is rolled and advanced therefrom in the form of a sheet or plate 4. The sheet formed by the rolls is shown as passing, in the present instance, down an inclined slide 5 and onto a subjacent transporting table 6, as well understood in the art.

It will be noted that in the use of an apparatus of this character fragmentary portions of the surfaces of the two rolls are exposed to the molten glass in the receptacle, so that such portions, both during a rotation of the rolls and when stationary, are more highly heated than the other portions of the rolls, thereby effecting an expansion of the metal at such point and the consequent forming of a bulge or hump on the roll

periphery. This irregular form of the roll surface imparts successive thick and thin sections to the rolled sheet, thereby necessitating greater work in the grinding operation to reduce the sheet surfaces to a true plane than would be necessary if rolls of true cylindrical form were used.

The rolls 3, 3 are of hollow form to facilitate the passage of a cooling fluid, such, 10 for instance, as air or water therethrough, as well understood in the art, the fluid being introduced into the roll and discharged therefrom through axial passages in the end trunnions 7 of the rolls. These trunnions, in the present instance, are provided 15 on end plates 8 secured to the roll in closing relation to the end openings thereof. In order to facilitate the rapid conduction of heat through the roll wall to the cooling 20 fluid the wall is preferably made quite thin, and in order to provide strength for such wall against inward deflection under rolling stresses and also to present a larger radiating surface to the cooling fluid, the inner 25 surface of the roll wall is provided with a plurality of webs or ribs 9, preferably running throughout the length of the roll and spaced transversely thereof.

By the use of a roll of this construction, 30 so far as I am aware, a more rapid transmission of heat from the hottest part of the roll to the cooling fluid will take place than with the forms of rolls heretofore used, and this will result in less distortion in the 35 roll and tend to maintain the shape of the same nearer that of a true cylinder than heretofore. It is possible with this form of roll to rotate it at a slower speed at the start of the rolling operation than is practical 40 with the rolls heretofore used and thereby produce a comparatively flat sheet with a blunter end than heretofore. On account of its more efficient cooling feature and the fact that it has a minimum of distortion 45 under varying heat conditions made possible by the use of the thinner walls, combined with the internal ribbing of the same, it is possible with the use of this roll to produce more glass of a uniform thickness 50 than can be produced, so far as I am

aware, with the types of rolls heretofore employed.

Having thus described my invention, what I claim as new and desire to secure by Letters Patent is:—

1. A roll for contact with and shaping molten glass, said roll being of hollow cylindrical form for the circulation of a cooling fluid therethrough and having the inner surface of its circumferential wall ribbed to 60 increase the heat radiating surface thereof.

2. A metal roll for contact with and shaping molten glass, said roll being hollow to permit the circulation of a cooling fluid therethrough and having a relatively thin 65 circumferential wall with the inner surface thereof ribbed to strengthen the wall against distortion under rolling stresses and to facilitate heat radiation to the cooling fluid.

3. A metal roll for contact with and shaping molten glass, said roll being hollow to permit the circulation of a cooling fluid therethrough and having a relatively thin circumferential wall with the inner surface 70 thereof longitudinally ribbed to reinforce 75 the wall against distortion under rolling stresses and to facilitate heat radiation to the cooling fluid.

4. In a sheet glass rolling apparatus, a receptacle for containing a batch of molten 80 glass, a pair of rolls exposed to the molten glass at one side of the receptacle and assisting in confining the molten glass within the receptacle, said rolls being spaced to adapt them to be turned to effect a rolling 85 of the glass in sheet form from the receptacle and being hollow to permit the circulation of a cooling fluid therethrough and one at least having a relatively thin circumferential wall permitting a rapid dissipation 90 of heat inwardly therethrough to the cooling fluid and having its inner peripheral surface ribbed to strengthen the wall against distortion under rolling stresses and to increase the heat radiating efficiency of the 95 roll.

In testimony whereof I have hereunto signed my name to this specification.

HAROLD R. SCHUTZ.
